UNITED STATES PATENT OFFICE.

NATHANIEL L. HURD, OF CHICAGO, ILLINOIS, ASSIGNOR TO SAMUEL M. LANGSTON COMPANY, OF CAMDEN, NEW JERSEY, A CORPORATION OF NEW JERSEY.

SCORING APPARATUS.

Application filed June 19, 1924. Serial No. 720,924.

To all whom it may concern:

Be it known that I, NATHANIEL L. HURD, a citizen of the United States, and resident of Chicago, in the county of Cook and State 5 of Illinois, have invented certain new and useful Improvements in Scoring Apparatus, of which the following is a specification.

This invention is an improved apparatus 10 to produce weakened lines in a box blank and along which the sheet may be folded. The main object of the invention is to facilitate the producing of score lines of any desired length by an adjustment of the parts 15 as distinguished from a substitution of parts.

In making box blanks it is common to form score lines along which the flaps may be bent in closing the ends of the box. If 20 relatively thick sheet material be employed it is desirable to form these lines staggered or with offset portions so that the lines along which two opposed flaps bend will be out of alignment with those along which the other two flaps bend, the amount of the offset 25 being equal to the thickness of the material. Each section of the score line will be of a length equal to the width of one side of the box, and therefore it is necessary to change the scoring mechanism to secure the 30 proper lengths of the relatively offset portions of the scored line each time a box blank of different width of side wall section is to be made.

Heretofore, this class of scoring has been 35 done by a pair of rotary scoring heads carrying cooperative arcuate scoring members cut or cast of the proper length and secured on the peripheries of the heads. Each new size of box blank necessitated the removal of 40 the old members and the attaching of new ones of different length. A large number of these arcuate members must be kept in stock or new ones ordered for each new box size. In addition to the trouble and expense 45 of frequently providing new scoring members, much time is lost in removing the old scoring members and in fastening the new ones accurately in place. Such change in every instance involves the added delay incident to properly aligning the scoring members of the two cooperating heads in accurate

mating relationship and in aligning the two pairs of heads for similar scoring at opposite ends of the blank. Often difficulty is encountered because the screw holes of the 55 new member do not match up with those in the head.

In the manufacture of various other blanks or forms of sheet material it is often that delay and expense are incurred 60 because of the necessity of varying the length or position of a scored weakened or cut line for different blanks or forms, even though there is no separate offset section of the line.

The present invention obviates the necessity 65 for keeping a varied stock of scoring members on hand or for substituting one scoring member for another each time a blank of different design is to be scored. As one important feature I provide supporting 70 heads having scoring members so constructed that by adjustment, the effective length and relative positions of the scoring portions may be altered without removing them from the heads. Preferably the scoring 75 members are flexible, or articulated so that operative or working portions may follow along the periphery of the scoring head and inoperative or non-working portions may be spaced inwardly from the periphery. 80 The scoring member is shiftable endwise to bring any desired length thereof into or out of effective scoring position. For producing staggered or offset scoring, one section 85 of each scoring member is laterally offset in respect to another section and the dividing line or point between these two sections may be moved along the periphery of the head and toward or from the point at which the member passes from operative to inoperative position. I am thus able to effect 90 the necessary adjustments of the length of the offset sections simply by shifting the flexible member endwise.

As another feature, I provide a series of 95 short scoring units or blocks which are so connected as to form an articulated member. Thus any member of said series may be held in operative position while, due to the flexibility of the connection, the remainder 100 may be held in inoperative position.

- As another feature of the invention, I provide a flexible scoring member in the form of an endless band having an operative run extending along the periphery of the head 5 and an inoperative run housed within the head. As another feature I provide a rotatable member such as a sprocket wheel to engage the member and shift it endwise when adjustment is desired.
- 10 As another feature of the invention the scoring member includes a flexible element upon which a series of scoring blocks or units are mounted, the blocks or units being shifted by the endwise movement of the 15 flexible element. Preferably the blocks are asymmetric and reversible to score on either side of a center line. A single set of blocks may thus be used for scoring a staggered line on the blank, the length of the relatively 20 offset portions being predetermined by the number or arrangement of the blocks on the strip, as well as by the endwise adjustment of the effective scoring portions of the member.
- 25 As another feature of my invention, I provide clamping or locking means independent of the means for adjusting the scoring members so that the parts are rigidly held for operation after being adjusted to 30 or assembled in the desired position.
- As a further feature of my invention, I provide a stationary or non-adjustable scoring member in addition to and disposed between a pair of the flexible endwise adjustable 35 scoring members so that, by having offset points intermediate of the end of each of the three members, the two offset points on the adjustable members may be moved toward or from the offset point on the non-adjustable member. Thus only two members need be adjusted to vary the length of each of the four successive portions of a box blank score line and corresponding in lengths 40 to the four sides of the box.
- 45 In the accompanying drawings, I have shown merely two of many embodiments of my invention.
- Fig. 1 is an end view of a pair of heads, certain of the parts being broken away, the 50 flexible scoring members being somewhat diagrammatically shown.
- Fig. 2 is a section on the line 2—2 of Fig. 1.
- Fig. 3 is a perspective view of connected 55 ends of the flexible strip which carries the scoring blocks.
- Fig. 4 is a perspective view of one of the scoring blocks, the strip being indicated in dotted lines.
- 60 Figs. 5 and 6 are sections on the lines 5—5 and 6—6 of Fig. 1, but on a larger scale.
- Fig. 7 is an edge view of a portion of one of the heads showing particularly the 65 non-adjustable scoring member.

Fig. 8 is a development of a portion of the periphery of the head.

Fig. 9 is an edge view of a modified type of head.

Fig. 10 is an end view of the construction 70 shown in Fig. 9, and including a fragment of a cooperating head.

Fig. 11 is a section on the line 11—11 of Fig. 10, and

Fig. 12 is a plan of a scored and slotted 75 box blank.

The particular forms of my invention which are disclosed in the present application are intended primarily for forming offset score lines for box blanks, although various features of the invention are equally applicable for forming continuous straight score lines or for otherwise acting upon sheet material.

In Fig. 12 I have shown a box blank having 85 four main sections, A, B, C, D of the proper size and shape to form the four walls of a box or carton. The four wall sections have end flaps a, b, c, d, at each end thereof, the several flaps being separated by slots e, 90 and the several wall sections being separated by scored or weakened lines f, g and h. The blank is also provided with score lines at the base or inner end of each flap to define the position at which the blank bends in folding 95 the flaps. If the material be comparatively thick, as for instance multiple-ply board or double-faced corrugated straw board, it is desirable that these last mentioned score lines be staggered so that the 100 flaps b and d may properly fold on top of the flaps a and c after the latter have been folded inwardly. Thus the score lines b' and d' are in alignment with each other but are offset from the score lines a' and c' 105 by a distance equal to the thickness of the material. The apparatus hereinafter described as particularly designed for forming these score lines a', b', c', d'.

In the apparatus as shown in Figs. 1 to 110 8 inclusive I provide a pair of scoring heads mounted on separate shafts 10 with their peripheries in relatively close cooperative relationship so that they will effectively score material passed therebetween. The 115 shafts may be journaled in any appropriate manner, and if desired, may be adjustable toward and from each other in accordance with the thickness of the material being acted upon. Obviously the heads are to be 120 driven at the same rate and in any appropriate timed relationship to the mechanism for feeding the sheet between the heads. Such parts of the machine are well understood in the art and form no portion of 125 my present invention. Therefore I have not illustrated them.

Each head is provided with a pair of flexible or articulated members each having a run or portion disposed in operative scoring 130

position on the periphery of the head and a portion spaced inwardly from the periphery and in inoperative position. The particular form of scoring member includes a plurality of short blocks or units 11 which are arranged along or strung on a flexible strip 12 which serves to connect the several scoring units and to permit of their relative movement. Each scoring unit 11 has an outer operative face 13 and suitable means for holding the unit on the strip 12. This means is illustrated as inturned flanges of hook-shaped ends 14 which engage with the inner surface of the strip. This connecting means does not prevent sliding of the units along the strip, but such sliding movement may be prevented by any suitable form of stops, as hereinbefore pointed out. Each unit is also provided with means whereby it may be rigidly clamped to the head. As shown, this means includes beveled outer ends 15, the bevel being on the outer surface, the under surface being flat. The main body portion 16 of the head is provided with a rim or cylindrical flange 17 at its periphery, and presenting an outer surface against which the scoring units may rest. Cooperating with the body of the head is a clamping plate 18 which is secured to the rim 17 in any suitable manner, as for instance by bolts or screws 19. The outer edge of the clamping plate and one edge of the body of the head extend outwardly beyond the outer surface of the flange 17, so as to form an annular groove on the head, and adapted to receive the scoring units. The opposite edges of this groove are undercut so as to engage with the beveled faces of the scoring units. Thus, when the screws 19 are tightened the units will be held firmly against the outer surface of the flange 17 and will be rigidly clamped in position. The clamping plate preferably has a flange 20 for engaging with the inner side of the flange 17 to resist any radially exerted strain on the clamping plate resulting from the cam action on the beveled faces of the scoring units during the tightening of the screws 19. The parts are so designed that the clamping plate does not directly engage with the end of the flange 17.

The flange 17 constituting the rim of the head is provided with apertures therethrough so that each flexible scoring member may be adjusted endwise to bring a portion thereof out of operative position on the outer surface of the rim. At each aperture in the rim there is preferably provided rollers or the like over which the flexible scoring member may pass. Preferably there is provided a roller 21 mounted on a stud bolt or other suitable axis carried by the body of the head and a pinion 22 somewhat similarly mounted. The head is provided with an annular groove 23 and the flexible

scoring member has its ends connected together within the head to form an endless band. The flexible scoring member thus extends along a section of the periphery, thence inwardly around the roller 21, thence through the annular groove 23 to the pinion or sprocket wheel 22, and thence out through the rim to the periphery. The head presents a flange 24 forming the inner wall of the groove 23, and the side of the groove is closed by the clamping plate 18 so that this groove forms a pocket or chamber for the inner or nonoperating run of the scoring member.

For adjusting the member endwise along the periphery the sprocket 22 is provided with teeth 25 for engaging in spaced apertures 26 in the strip 12. Each scoring unit has a recess 27 in the under surface thereof which permits the free passage of the sprocket teeth 25 through the apertures 26. The two ends of the strip 12 may be secured together in any suitable manner. For instance I have shown in Fig. 3 the two ends secured between a pair of locking plates 28 which are secured together by suitable screws. The scoring units or blocks are strung along the entire length of the band so that the clamping plates 28 serve as stops to prevent any sliding movement of the units. If a smaller number of the units be employed, obviously special stops independent of the plates 28 might be employed. Each toothed pinion or sprocket wheel 22 may have a squared hub portion 29 projecting beyond the clamping plate 18 whereby it may be rotated to move the scoring member endwise when the screws 19 are loosened.

The roller 21 and the sprocket 22 are spaced nearly 180° apart along the periphery of the head so that the two rollers 21 for the two flexible scoring members may be mounted closely adjacent to each other at one side of the wheel and the two sprocket wheels closely adjacent to each other at the opposite side of the wheel. Thus the major portion of the periphery of the head will be provided with operative runs of the two flexible scoring members. Preferably the clamping plate 18 is made of two sections, one for each flexible member, so that one plate may be loosened and its corresponding member adjusted without disturbing the adjustment of the other.

As one important feature the scoring units have their operating faces materially offset in respect to the center or medial line of the strip 12. The distance to which these faces are thus offset is equal to one-half the distance to which it is desired to offset one section of the scored line in respect to another. Thus by arranging some of the units on the strip with their operative faces at one side of the medial line and the remainder of the

units with their operating faces at the other side of the medial line, these operating faces will act to produce two score lines which are offset in respect to each other to the desired 5 distance. All of the scoring units are thus identical but the offsetting of the score line is secured by a mere reversal of the position of the scoring units on the strip.

For scoring such a continuous staggered 10 line as the line a' , b' , c' , d' of Fig. 12, the head is provided with an additional scoring member acting as a filler piece on the periphery of the head between the two rollers 21. This is shown particularly in Fig. 15, 7, and includes two sections 30 and 31 which are rigidly secured in place in any suitable manner, as for instance by screws. These 20 two sections have their operating faces similar to those of the other scoring units 11, but have them oppositely offset in respect to the medial line. By arranging the units as shown in Fig. 8, it will be apparent that any desired adjustment to produce box blanks with the sides A, B, C, D of various 25 widths, may be secured by the endwise adjustment of the two flexible units. In adjusting the machine the feed mechanism is brought to such position in respect to the heads that the line g of the blank will come 30 at the point indicated by the letter "g" on Fig. 8, which is the dividing line between the two non-adjustable scoring sections 30 and 31. One of the flexible members is adjusted endwise until the dividing line 35 (marked "h" in Fig. 8) between one set of units 11 and the other set in reverse position, is at a distance (marked "C" in Fig. 8) equal to the width of the blank section C. The other flexible member is adjusted endwise until its corresponding dividing line f 40 is at a distance B from the line g equal to the width of the blank section B. The portion of one flexible member beyond the line f will act to score the line a' of the blank; 45 the other section of the flexible member and the stationary scoring section 30 together will score the line b' of the blank; the stationary scoring section 31 and the portion of the other strip to the point h will score 50 the line c' ; and the first part of the last mentioned scoring member beyond the point h will score the line d' . Obviously the portions of the two flexible members beyond the points f and h may extend beyond the 55 edge of the blank and in ordinary practice will do so. The adjustment of the feeding mechanism in respect to the head merely serves to bring the center line g of the blank to the non-adjustable joint g of the head.

For scoring the two lines a' , b' , c' , d' of the blank at the proper distance apart, it is necessary to provide two pairs of heads. These are mounted for relative axial adjustment on their respective shafts. Preferably each head has a split hub 32 with a

clamping screw 33 for tightening it and locking the head in position. Each shaft is preferably provided with a keyway or spline 34 which has its outer surface provided with teeth so as to constitute a rack bar and the 70 hub is provided with a pinion 35 mounted between lugs and provided with suitable means, as for instance a squared end shaft 37, for rotating the pinion. By loosening the screw 33 the pinion may be rotated to 75 axially adjust the head to the desired position. The spline serves not only as a part of the adjusting mechanism but also serves to prevent any rotation of the head on the shaft. 80

I have heretofore referred to the operating faces of the scoring units but have not described such faces in detail. It is obvious that these faces may be of any desired character, depending upon the kind of material 85 acted upon or the score line to be produced. Preferably the units used on the two cooperating heads should be of male and female type, as indicated in Fig. 5.

This application is in part a continuation 90 of my prior application, Serial No. 633,866, filed April 23, 1923. In Figs. 9, 10 and 11 I have illustrated a form which was illustrated in said application. In the form here shown the flexible members are of the 95 same general character in that they are made up of articulated or flexibly connected units and are endwise adjustable in a peripheral groove of the head so that when the clamping plate is loosened more or less 100 of each member may be moved into inoperative position within the head. The head 16^a is provided with a clamping plate 18^a which cooperates therewith to form a peripheral groove in which are mounted the units 11^a. 105 The two ends of each unit are not connected to form an endless band, but one end is movable along the groove while the other end may move into or out of a pocket or chamber 23^a within the head. Between the 110 apertures in the head and through which the flexible members extend, are the stationary or non-adjustable scoring units 30^a and 31^a.

In the prior application above referred to I have illustrated another embodiment of 115 my broad invention and in which flexible scoring members are used in connection with slitting members. Many of the features of such embodiment are within the scope of the claims of the present application. 120

Although the units 11 or 11^a of the apparatus hereinbefore described are intended primarily for scoring a sheet, that is, for imparting to it a weakened line, it will be evident that by varying the character of the 125 operating faces of the units they might act to perform other operations on a sheet of material passing between the two heads. They might include, for instance, cutting edges which would completely sever the 130

sheet along a continuous or broken line or might form a row of perforations in the sheet, or otherwise act on it.

From the foregoing description it will be

5 apparent that I have provided a head for scoring or other operations, which may be very easily adjusted to produce score lines of different lengths, and without the necessity for any substitution of parts.

10 Having thus described my invention, what I claim as new and desire to secure by Letters Patent is:—

1. In a device of the class described, a rotatable head having a flexible scoring member 15 adjustably mounted thereon and supported throughout its length by said head.

2. In a device of the class described, a rotatable head having an opening in the periphery thereof and a flexible scoring member 20 extending along the periphery and through said opening.

3. In a device of the class described, a supporting head having a flexible scoring member carried thereby and having portions offset with respect to each other for 25 scoring a blank along a staggered line.

4. In a device of the class described, a supporting head having an opening therein and a flexible scoring member carried there- 30 by along the periphery thereof and adjustable endwise through said opening.

5. A rotatable scoring head having a flexible scoring member extending along the periphery thereof, a portion of said mem- 35 ber being concealed within the head.

6. A rotatable scoring head having a scoring member including a series of short units connected together and shiftable endwise along the periphery of said head.

40 7. A scoring device having a scoring member including a series of short identic asymmetric units, certain of said units being assembled in reversed relationship to the others to produce an offset score line.

45 8. A scoring device having a scoring member made up of an articulated series of similar asymmetric short units.

9. A scoring device having a scoring member including a series of short identic 50 asymmetric flexibly connected units, certain of said units being assembled in reversed relationship to the others to produce an offset score line.

55 10. A rotatable scoring head having a peripheral groove and a scoring member disposed in said groove and including a series of short blocks or units connected together.

60 11. A rotatable scoring head having a peripheral groove and a scoring member dis- posed in said groove and including a series of short blocks or units flexibly connected together.

65 12. A rotatable scoring head having a peripheral groove and a scoring member dis- posed in said groove and including a flexi-

ble element and a series of units strung thereon.

13. A rotatable scoring head having a groove in the periphery and a flexible scor- 70 ing member clamped therein.

14. A rotatable scoring head having a groove in the periphery a flexible scoring member mounted therein and adjustable lengthwise thereof and means for clamping said member rigidly to said head. 75

15. A rotatable scoring head having a groove in the periphery and a flexible scoring member mounted therein, the opposite sides of said groove being movable toward and from each other to clamp said member. 80

16. A rotatable scoring head having a peripheral groove and a scoring member disposed in said groove and including a series of short blocks or units connected together, the opposite sides of said groove 85 being movable toward and from each other to clamp said member.

17. A rotatable scoring head having a peripheral groove and an aperture and a scoring member disposed in said groove and 90 adjustable endwise through said aperture.

18. A rotatable scoring head having a flexible scoring member mounted thereon and comprising an endless band, a portion only of said band constituting an effective 95 scoring run and located on the periphery of the head and another portion being spaced inward radially in respect to the operative run.

19. A rotatable scoring head having a flexible scoring member mounted thereon and comprising a band, a portion only of said band of a length not greater than the periphery of the head constituting an effective scoring run and located on the periphery of the head. 100

20. A rotatable scoring head having a flexible scoring member mounted thereon and comprising an endless band, a portion thereof extending along the periphery of the head and another portion being concealed within the head. 110

21. A rotatable scoring head having a flexible scoring member mounted thereon and comprising a band, a portion thereof 115 extending along the periphery of the head and another portion being concealed within the head.

22. A rotatable scoring head having a flexible scoring member carried thereby and having its effective scoring portion disposed upon the periphery of the head, and means for shifting the scoring member endwise. 120

23. A rotatable scoring head, having a flexible scoring member carried thereby and having its effective scoring portion disposed upon the periphery of the head, and a sprocket wheel for shifting the scoring member endwise. 125

24. A rotatable scoring head, having a 130

- flexible scoring member carried thereby, an effective scoring portion thereof being disposed upon the periphery of the head and an inoperative portion being concealed within the head, and means engaging with said member to adjust the same endwise. 5
25. A rotatable scoring head, having a flexible scoring member carried thereby, an effective scoring portion thereof being disposed upon the periphery of the head and an inoperative portion being concealed within the head, means engaging with said member to adjust the same endwise, and independent means for rigidly clamping said member. 10
26. A rotatable scoring head, having a flexible scoring member carried thereby, an effective scoring portion thereof being disposed upon the periphery of the head and an inoperative portion being concealed within the head, and means concealed within the head and engaging with said member to adjust the same endwise. 15
27. A rotatable scoring head having a peripheral groove and an aperture, a scoring member disposed in said groove and adjustable endwise through said aperture, and a sprocket wheel within the head adjacent to said aperture for adjusting said member. 20
30. 28. A scoring head having a flexible scoring member including a flexible strip and a plurality of scoring blocks carried by the strip, a rotatable member carried by the head for moving said scoring member endwise, and means engaging with said blocks for clamping them in position. 35
29. A scoring head having a flexible scoring member including relatively offset scoring portions to form a staggered score, and means for adjusting the relative effective lengths of said portions. 40
30. A scoring rotatable head having a flexible scoring member including relatively offset portions, means for adjusting said portions endwise to vary the position of the dividing point between said portions circumferentially of the head. 45
31. A scoring head having a peripheral wall and an annular channel adjacent thereto, a flexible scoring member including an operative portion extending along the outer surface of said wall and an inoperative portion disposed within the channel. 50
32. A scoring head having a pair of apertures spaced apart along the periphery, rotatable members adjacent to said apertures, and an endless scoring member extending through both apertures and around both rotatable members, and having an operative portion extending along the periphery. 55
33. A scoring head having a pair of passages therethrough and a pair of flexible scoring members each including relatively offset scoring portions and each having an operative portion disposed along the periphery, and an inoperative portion disposed within the corresponding passage. 60
34. A scoring head having a pair of passages therethrough and a pair of flexible scoring members, each having an operative portion disposed along the periphery, and an inoperative portion disposed within the corresponding passage. 65
35. A scoring head including a peripheral rim and a channel adjacent the rim, and endless flexible scoring bands having operative runs disposed on the rim and inoperative runs disposed within the channel, said rim having openings therein to permit the entrance of the bands into the channel. 70
36. A scoring head including a peripheral rim and a channel adjacent the rim, and endless flexible scoring members having operative runs disposed on the rim and inoperative runs disposed within the channel, said rim having openings therein to permit the entrance of the bands into the channel, and each of said members having two offset portions for scoring a staggered line. 75
37. A scoring head having an annular chamber adjacent to the rim, a plurality of endless flexible members each having an operative scoring run disposed on the rim and a run disposed within said chamber, said rim having openings therein to permit the passage of the members therethrough to said chamber, and a relatively stationary scoring member secured on the rim between said openings whereby the several members may produce a continuous score. 80
38. A scoring head having a pair of openings through the rim, a scoring member extending along the rim between the openings and a pair of scoring members each extending along the rim and in opposite directions from the first mentioned member, said pair of members being endwise adjustable through said openings. 85
39. A scoring head having a pair of openings through the rim, a scoring member extending along the rim between the openings and a pair of flexible scoring members each extending along the rim and in opposite directions from the first mentioned member, said pair of members being endwise adjustable through said openings. 90
40. A scoring head having a pair of openings through the rim, a scoring member extending along the rim between the openings, and a pair of scoring members each made up of an articulated series of short units and extending along the rim and in opposite directions from the first mentioned member, said pair of members being endwise adjustable through said openings. 95
41. A scoring head having a flexible scor- 100
- 105
- 110
- 115
- 120
- 125

- ing member carried on the periphery thereof, and a clamping member for holding said scoring member against endwise movement relative to the head.
- 5 42. A scoring head having a scoring member carried on the periphery thereof, and including an articulated series of short units, and a clamping member for holding said scoring member against endwise movement 10 relative to the head.
43. A head having a chamber therein, a peripheral rim, a flexible device for acting on a sheet of material and including a portion disposed in operative position on the 15 rim and a portion in inoperative position within said chamber, means for shifting said device endwise, and a clamping plate cooperating with the rim to clamp said device in position.
- 20 44. A head having a chamber therein, a peripheral rim, a flexible device for acting on a sheet of material and including a portion disposed in operative position on the rim and a portion in inoperative position 25 within said chamber, means for shifting said device endwise, and means for clamping the first mentioned portion to the rim.
45. A head having a chamber therein, a peripheral rim, a flexible device for acting on a sheet of material and including a portion disposed in operative position on the rim and a portion in inoperative position 30 within said chamber, and a clamping plate cooperating with the rim to clamp said device in position.
- 35 46. A rotatable head, having a flexible device carried thereby for acting on a sheet of material, and having an operative run on the periphery and an inoperative run concealed 40 within the head, and a pair of rotary members at the ends of the operative run, one of said members comprising a toothed pinion engageable with said device to move the latter endwise.
- 45 47. A rotatable head having a flexible device carried thereby for acting on a sheet of material and comprising an endless band having an operative run on the periphery and an inoperative run concealed within the 50 head, a pair of rotary members at the ends of said operative run, one of said members comprising a pinion rotatable to effect end-
- wise movement of said device, and a handle for rotating said pinion.
48. A rotatable head having a groove 55 therein, a flexible device within the groove for acting on a sheet of material and a clamping plate secured to the head and co-operating therewith to clamp said device in the groove.
- 60 49. A rotatable head including a rim portion, a pair of flexible endless bands each having an operative run located on the rim, and an inoperative run disposed within the head, said rim having openings therein to 65 permit the entrance of the band into the head and a filler member disposed on the rim between said openings.
50. A scoring device comprising a strip of flexible material having slots therein, and 70 a plurality of scoring units threaded on the strip and having recesses on their under faces registering with the slots.
51. A scoring device comprising a flat flexible strip and a plurality of scoring 75 blocks including scoring portions offset relative to the medial line of the strip.
52. A scoring block having a scoring face, hook shaped extremities and beveled ends.
53. A scoring device including a flat flexible strip having a series of apertures therein, and a series of scoring units disposed along 80 the strip.
54. A scoring head having an opening through the rim thereof, a relatively stationary scoring device at one side of said opening, and a second scoring device at the other side of said opening and movable endwise into and out of said opening.
- 85 55. In a device of the class described, a head having an opening therein, a flexible scoring member adjustably carried by said head, and having a portion extending through said opening, and a relatively stationary scoring member secured to said head 90 adjacent to said opening, and upon the opposite side of the latter from the operative portion of the first mentioned scoring member.
- 95 Signed at Chicago in the county of Cook, 100 and State of Illinois this 16th day of June
A. D. 1924.

NATHANIEL L. HURD.
